ELECTRIC MUSICAL INSTRUMENT

William C. Wayne, Jr., Cincinnati, Ohio, assignor to
The Baldwin Piano Company, Cincinnati, Ohio, a cor-
poration of Ohio

Filed Oct. 9, 1953, Ser. No. 385,138
17 Claims. (Cl. 84—1.01)

My invention relates generally to electric musical instruments of the type wherein electric oscillations corresponding in characteristics to tones of the usual equally-tempered musical scale are produced by a set or series of sources of such oscillations, selected by one or more keyboards, combined and/or modified for various tone colors and converted to sound by electro-acoustic means.

In particular, my invention concerns methods and systems for creating, from such instruments wherein a *single set only* of sources of such oscillations is present, "ensemble" and other effects which heretofore have been obtainable *only* from an instrument having a *plurality of sets* of sources. The ensemble or chorus effect is similar to that of a celeste tone color in a pipe organ, which is produced when each organ key simultaneously sounds two or more pipes intentionally tuned to slightly different pitch.

By way of general background for a better understanding of certain principles underlying my invention, it has been pointed out by Hammond et al. in U.S. Patent No. 2,498,367 issued February 21, 1950, that "the richness of most musical tones may be greatly enhanced by the utilization of several tone generating sources, all of which sound simultaneously to produce a chorus effect. This effect is commonly observed in orchestras where it is not unusual to see a relatively large number of musicians playing the same note on the same kind of instrument. The explanation of the resulting beauty of their composite tonality resides in the fact that the musicians inadvertently play at slightly different pitches. The result is an interesting and pleasing tonal undulation. If all the musicians were to play at exactly the same pitch, the resulting effect would be substantially identical to that produced by a single player save for a somewhat increased loudness due to the multiplication of the number of instruments. These inadvertent differences in pitch, while productive of a very noticeable change in quality, are actually very small, their mutual deviation factor being a fraction of a percent. Apparatus for producing similar chorus effects have also been provided in organs, accordions, harpsichords and the like." For example, as pointed out above, the celeste stop on a pipe organ will bring simultaneously into play two or three ranks of pipes, so that when one organ key is depressed, two or three pipes of slightly different pitch will sound. Quoting Hammond further: "That these chorus effects are beautiful cannot be denied. Their effect musically is of fundamental importance in orchestras, keyboard instruments, and choruses of voices."

In an electric organ in which a *single* set of generators of electric oscillations (corresponding in characteristics respectively to the musical tones produced), and *particularly* in such an organ wherein generators in the set are interlocked as to frequency relationships, the ensemble of the music produced lacks the musically desirable chorus effect described above. To overcome this fact some workers in the art have followed the expensive and expansive practice of employing *two or more complete* sets of generators and of deliberately detuning them slightly, note-for-note, from the nominal pitch to accomplish a chorus effect. Although this is analogous, of course, to pipe organ practice, wherein, as pointed out above, several pipes for each note of a celeste tone color are sounded simultaneously, it is nevertheless an

2

elaborate and uneconomical procedure in view of methods and means such as I disclose herein. Furthermore, if the frequencies of the generators in a multiple-set instrument are *not* locked together in some way, the problem of individual tuning of each source becomes burdensome. Consequently, my invention has for an important object the teaching of a simple, practical and relatively inexpensive method for producing a celeste effect in an electric musical instrument having only *one* set of sources of electric oscillations respectively corresponding to the notes of the usual *equally tempered* musical scale.

Another important object of my invention is to provide an electric musical instrument having tone colors simulating those of celeste ranks in a pipe organ.

A further object is to provide an instrument as in the preceding object, in which the fundamental and harmonic frequency components of each tone are phase and amplitude-modulated at sub-audio rates which progressively increase with pitch.

It is believed that certain ancillary objects of my invention may be comprehended more readily following a definition of certain terminology to be used herein. The term "footage" denotes pitch range with respect to normal pitch. Usually, in pipe organ practice, "8 ft." pitch is the normal for a given *manual* key, while "16 ft." pitch is the normal for a *pedal* key. The terms were derived originally from the lengths of pipes. So, for example, if a stop-tab for a *manual* tone-color designated as *Diapason 8'* is chosen, then when a *manual* key is depressed, the pitch of the note produced will be the normal for the key. If, then, a *Flute 4'* stop is selected, the pitch of the note produced by the same key will be an octave *above* the normal (8 ft.) pitch. Similarly, a 2 ft. stop will produce a note *two* octaves *above* the 8 ft. pitch or one octave above the 4 ft. pitch. The selection of a 16 ft. tone-color will result in a tone an octave *below* the 8 ft. tone.

Now, in a *pedal* keyboard, 16 ft. is *normal* pitch, so a 32 ft. tone-color will produce a tone one octave below the normal (16 ft.) pitch.

A further object, then, of my invention is to provide an improved simple method and means for obtaining 32 ft. tone-colors from a *pedal* keyboard in an electric organ without the need for actual sources of oscillations for the lowest octave compass of notes.

A still further object is to provide means for producing in an electric organ at least one mixture tone-color (that is, one of combined footages, such as 4 ft. and 2½ ft. for a given stop-tab) without the necessity for an extra deck of key switches for certain additional footages.

Another important object is to provide an improved simplified circuit means for an electric organ whereby celeste, mixture and 32 ft. tone-colors may all be produced from a *single* set of generators fewer in number than the individual notes to be produced and with fewer key switches than have heretofore been necessary.

These and other objects which may be set forth hereinafter or will be apparent to one skilled in the art upon reading these specifications, I accomplish by those circuits and arrangements of parts of which I shall now set forth exemplary embodiments. Reference is made to the accompanying drawings, wherein:

FIGURE 1 is a block diagram illustrating certain basic principles of my invention;

FIGURE 2 is a simplified schematic diagram illustrating a basic circuit of my invention;

FIGURE 3 is a schematic diagram showing a further principle of my invention;

FIGURE 4 is a schematic diagram illustrating an alternate to the system of FIGURE 3;

FIGURE 8 is a simplified circuit diagram of an analytic type electronic organ employing certain teachings of my invention which, in this instance, are applied to a pedal keyboard; and

FIGURE 9 is a chart showing the relationships between unison and celeste frequencies throughout more than one octave.

The fundamental concept

The fundamental concept of my invention is based upon the *inherent "out-of-tuneness"* of certain musical intervals in the equally-tempered musical scale, in which adjacent half-tones are related in the ratio of

$$\sqrt[12]{2}:1$$

For example, the *tempered* fifth is *not* a "perfect" or integral ratio, as is the fifth in the *just* scale, the former being in the ratio of

$$\sqrt[12]{27}:1$$

(1.4983:1 when expressed as a decimal ratio), while the latter ratio is 1.5000:1 (or the integral ratio of 3:2).

Another example is the tempered fourth, which is the ratio of

$$\sqrt[12]{25}:1$$

whereas the perfect fourth is in the ratio of 4:3, another integral ratio.

Broadly, according to one aspect of my invention, I combine, for each note to be produced, a pair of periodically oscillating voltages which may be harmonically complex in nature (in order to correspond in characteristics to harmonically complex musical tones) whose fundamental frequency components correspond respectively to one of the above-mentioned "certain intervals in the equally-tempered musical scale," the combination being carried out by a *modulation* process in such a way as to produce sum-frequency and/or difference-frequency voltages having, if the original two voltages are complex, a series of harmonically related components based on the fundamental frequency of the difference-frequency voltage so produced. For example, if a voltage corresponding to a tone C_4 (261.626 c.p.s.) is combined as described above with a voltage corresponding to a tone G_4 (391.995

Case I—Amplitude Modulation (nonlinear combination)

Let e_m be the amplitude modulated wave produced by the *non-linear* combination of e_1 and e_2 . Let e_1 be the carrier wave whose amplitude is made proportional to the instantaneous value of the modulating signal wave e_2 through the action of the non-linear device.

Assume $e_1 = E_1 \cos \omega_1 t$
 $e_2 = E_2 \cos \omega_2 t$

According to the above definition of amplitude modulation, E_1 is a function of time and can be expressed as

$$E_1(t) = E_1 + kE_2 \cos \omega_2 t$$

where k is a proportionality constant. Therefore,

$$e_m = [E_1 + kE_2 \cos \omega_2 t] \cos \omega_1 t$$

or, $e_m =$

$$\text{term (1)} \quad [kE_2 \cos \omega_2 t] \cos \omega_1 t$$

$$\text{term (2)} \quad + [E_1 \cos \omega_1 t]$$

Example

Suppose that f_1 (the carrier) is 101 c.p.s. and f_2 (the modulating signal frequency) is 1 c.p.s.

Inspection shows that e_m is a wave made up of two terms:

(1) A wave of frequency 101 c.p.s. whose phase reverses twice a second and whose amplitude varies cyclically twice a second, thus, the average value over an integral multiple of two amplitude beat cycles is zero.

(2) A wave of frequency 101 c.p.s. of constant amplitude and phase.

c.p.s.), the difference-frequency will be 130.369 c.p.s. (corresponding *nearly* to a note C_3 at 130.813 c.p.s.—an octave below C_4) with harmonic frequency components depending upon the existence and relative strengths of the harmonic components of the C_4 and G_4 voltages combined, as will be described in detail hereinafter. As will be pointed out below in the discussion of FIGURE 2, some celeste effect is produced as the result of certain modulation products differing slightly from components of one or both of the voltages applied to the modulator. However, in order to more nearly simulate a pipe organ celeste, wherein the fundamental and each harmonic of one pipe "beat" with the fundamental and the respective harmonic of another pipe, I may, as another step of my invention, *linearly* combine this derived voltage with another voltage harmonically related to one of the voltages of the *original* pair and which, at the same time, is close in frequency to the "derived" voltage. This unison voltage may, for example, be provided by means of frequency division from one of the voltages in the original pair.

The block diagram of FIGURE 1 illustrates these basic steps of my invention. Voltages corresponding to notes C_4 and G_4 , derived from sources 2 and 4, respectively, are fed to a modulator 6 of a type subsequently to be discussed. The derived voltage at a fundamental frequency of 130.369 c.p.s. is fed to an adding network 8 along with a "unison" voltage at 130.813 c.p.s. which may be derived by frequency division in a suitable frequency divider 10. Circuit details will be described in connection with FIGURES 2, 3, 4, 5a, 5b, and 6.

This *linear* addition in the network 8 yields a complex voltage whose magnitude is characterized by slow undulations in amplitude, commonly called beats, that occur in its fundamental and harmonics (if any are present) as well as a complete phase reversal once each beat cycle so that, when converted to sound in an electro-acoustic system of the usual type, a celeste or chorus effect is produced. The phase reversals occur at such a low repetition frequency that they are inaudible. Therefore, the listener senses only the *amplitude modulation* although mathematical analysis shows that the *beat* wave has both phase- and amplitude-modulation characteristics.

In order to clarify *amplitude modulation* and *beats*, two processes which are both involved here in the production of celeste, a mathematical analysis of each follows, which includes specific examples and discussions of the output waves.

The relation between a wave having *amplitude modulation* characteristics and a *beat* wave may be illustrated by the parallel cases:

Case II—Beats (linear combination)

Let e_b be the beat wave produced by the *linear* combination of e_1 and e_2 . Assume e_1 is the unison voltage and e_2 is the derived voltage. The angular velocity ω_1 slightly exceeds ω_2 .

$$\begin{aligned} e_1 &= E_1 \cos \omega_1 t \\ e_2 &= E_2 \cos \omega_2 t \\ e_b &= e_1 + e_2 = E_1 \cos \omega_1 t + E_2 \cos \omega_2 t + [E_1 \cos \omega_1 t - E_2 \cos \omega_2 t] \\ &= E_2 [\cos \omega_1 t + \cos \omega_2 t] + [E_1 - E_2] \cos \omega_1 t \end{aligned}$$

$$e_b = [2E_2 \cos \left(\frac{\omega_1 - \omega_2}{2} t \right)] \cos \left(\frac{\omega_1 + \omega_2}{2} t \right) + [E_1 - E_2] \cos \omega_1 t$$

If f_0 is the celeste tone audio frequency

$$f_0 = \frac{f_1 + f_2}{2}, \quad \omega_0 = 2\pi f_0 = \frac{\omega_1 + \omega_2}{2}$$

If f_b is the beat sub-audio frequency

$$f_b = \frac{f_1 - f_2}{2}, \quad \omega_b = 2\pi f_b = \frac{\omega_1 - \omega_2}{2}$$

Substituting, $e_b =$

$$\begin{aligned} \text{term (1)} & \quad [2E_2 \cos \omega_0 t] \cos \omega_0 t \\ \text{term (2)} & \quad + [E_1 - E_2] \cos \omega_1 t \end{aligned}$$

Example

Suppose that f_1 is 102 c.p.s. and f_2 is 100 c.p.s. Then f_0 is 101 c.p.s. and f_b is 1 c.p.s.

Inspection shows that e_b is a wave made up of two terms:

(1) A wave of frequency 101 c.p.s. whose phase reverses twice a second and whose amplitude varies cyclically twice a second, thus, the average value over an integral multiple of two amplitude beat cycles is zero.

(2) A wave of frequency 102 c.p.s. of constant amplitude and phase.

Observe that terms (1) are identical in both cases. Terms (1) include the combined upper and lower sidebands of frequencies 102 c.p.s. and 100 c.p.s., respectively. Thus, it can be seen that the difference between Case I and Case II occurs in the frequency inequality of the two terms (2). Because of the phase reversals noted, no electrical power can be supplied at a frequency of 101 c.p.s. in either case from terms (1), but can be supplied by term (2) Case I. However, useful celeste output is obtained at 101 c.p.s. from term (1), Case II since the overall hearing system does not detect the sub-audio frequency phase reversals. Identical waves may be obtained involving only terms (1) from both cases if terms (2) are eliminated. This is accomplished in Case I by using a balanced modulator which suppresses the carrier, i.e., term (2), and, in Case II by choosing E_1 to equal E_2 in amplitude. The number of beats per second heard by an observer in the example, Case II, is two per second which, at first glance, would not appear to be in accord with the mathematical value of

$$f_b = \frac{f_1 - f_2}{2} = \frac{102 - 100}{2} = 1 \text{ c.p.s.}$$

Again, this is a manifestation of the fact that (at sub-audio beat frequencies) the overall hearing system regards one beat wave just as the following beat wave, although the latter has undergone a complete phase reversal. Mathematically, only one complete beat cycle per second occurs but practically, the observer responds to two complete beat cycles per second. The usual formula to be found in physics textbooks that f_b is f_1 minus f_2 should be qualified accordingly.

In accordance with the foregoing, if the derived voltage of 130.369 c.p.s. is linearly combined with a voltage corresponding to C_3 (130.813 c.p.s.) an exact octave below (or one-half the frequency of) C_4 of the original pair, an audible beat rate of .444 c.p.s. (130.813 - 130.369) will result.

As a step of my invention *alternate* to the one just described wherein *voltages* are linearly *combined* before conversion to sound, I may convert the "derived voltage" to sound in one appropriate electroacoustic system and simultaneously convert to sound in another electroacoustic system another voltage harmonically related to one of the voltages of the *original* pair and which, at the same time, is close in frequency to the "derived voltage," the *linear* combination being accomplished in the air or medium in which the sound is produced. The procedure will be described in detail in connection with FIGURES 4 and 6. Before proceeding with a detailed description of my invention I shall discuss pertinent acoustical principles involved herein.

Background and prior art

By way of background, to distinguish my invention from the prior art, it has long been known that there can be created in the ear a *subjective* tone of a given frequency even though *physically* there are no sound waves of that frequency present (Seashore, Psychology of Music, McGraw-Hill, 1938). For example, if pure tones having frequencies of 400, 600, 800, etc. cycles per second are sounded simultaneously, the *sensation* of hearing a 200 c.p.s. note will be had by the listener. This phenomenon has been employed by pipe organ designers, who *produce* the *effect* of a very low note (which, to *produce physically*, requires a very long pipe) by sounding two smaller pipes whose pitch *difference* is equal to one-half the frequency of the lower of the two pipes. The subjective tone thus produced has been called a "resultant" or "differential" tone (Audsley, Art of Organ Building, Dodd-Mead, 1905). A currently manufactured electronic musical instrument employs this phenomenon in producing each bass note in its lowest octave by feeding to a loudspeaker system the algebraic sums (obtained from electrically *linear* adding

networks) of two oscillating voltages related as to fundamental frequency by an interval corresponding to a fifth in the musical scale (a ratio of *about* three to two in the equally-tempered scale), the upper of the two voltages being *reduced* as to amplitude. The frequencies are near enough to a 3:2 ratio that the instrument can produce to a moderate degree the *subjective effect* of a series of low notes, for which *in the instrument, there are actually no oscillating electric voltages corresponding in frequency to the low notes*.

In one prior art circuit, the electric oscillations produced by two generators correspond in fundamental frequency, for example, to the notes G and D, respectively, and are combined at a connection after passage 5 through two decoupling resistors, respectively. The resistance of one resistor is several times that of the other resistor, so that the tone produced by the system will not contain an excessive amount of the D frequency, which would mask the subjective effect, (produced in 10 the ear of the listener) of the G frequency an octave below that of the G frequency produced by the generator. If the key switch connecting the junction to ground is open, the algebraic combination of the oscillations produced by the generators is permitted to pass along 15 through a resistor, through a filter system, an amplification system and an electroacoustic system. In this known type of instrument the combination of the oscillations from the two generators is strictly a linear, algebraic one and electric oscillations corresponding in 20 fundamental frequency to the note G *below* that produced by the first generator are *not actually present* in the circuit.

Another prior art system (U.S. Patent No. 2,561,349 to C. W. Earp) starts with a source of electric oscillations 25 which are passed through two separate paths to a modulator to which, in series, are connected a filter system and electroacoustic projector means. In one of the two paths just mentioned is a frequency divider and a filter.

The frequency divider divides by integral powers of 30 2, and the modulation output contains a difference-frequency component, which is converted to sound to produce a lower frequency tone which is an *integral* sub-multiple of the fundamental frequency of oscillations from the source, the purpose being to achieve a loudness 35 level which is directly proportional to the strength of the original input oscillations. The narrowest common ground of similarity between Earp's teachings and mine is that of feeding two audio frequency components of 40 the *order of one-half* of the frequency of one of the input voltages. From this common ground in the art, which is new neither with Earp nor with me *so far as basic circuitry is concerned*, Earp, of *necessity* uses an 45 integral frequency divider to provide one of his input oscillations so as to obtain a frequency which is an *integral* sub-multiple of the frequency of one of the original oscillations. I have found that feeding to a modulator a pair of voltages related in frequency as 50 certain intervals of the equally-tempered scale will produce modulation product voltages usable either with or without algebraic combination with other voltages to accomplish chorus and other effects. It will be seen that 55 one of the basic differences between Earp's system and mine is that I purposely produce a lower frequency tone which is *not* integrally related (as to frequency) to one 60 of the original oscillations.

It should be pointed out that neither of these two prior art systems provide a chorus effect in which the effect of two or more notes of *nearly* the same pitch are produced simultaneously.

Basic circuit of my invention

According to my invention, a basic exemplary circuit of which is illustrated in FIGURE 2, I preferably feed 75 oscillations corresponding to *tempered* fifths of a musical

scale from two generators 33 and 35 through two decoupling resistors 37 and 39, respectively, and two key switches 41 and 43, respectively, to a square-law modulator 45. For the purpose of this disclosure, a square-law modulator may be defined as a circuit element whose current-voltage characteristic is such that the current through the element depends on the second power or square of the impressed voltage. The output of the modulator 45 may be fed through a tone-color filter 53, selectively coupled by means of a stop-switch 54 to an output system, which may comprise an audio amplifier 55 and an electroacoustic translator 57, for conversion of the tone voltages to sound. The tone-color filter 53 may be of the low-pass, high-pass, band-pass or other type known in the art. Examples are shown in Kock Patent No. 2,233,948.

As will be apparent to one skilled in the modulation art, the output tones of the system, as mentioned briefly above, will be phase and amplitude-modulated at sub-audio rates. This comes about by the fact that, the respective fundamental and harmonic frequencies of the generators 33 and 35 are not integrally related; thus modulation products exist in the output which differ in frequency by small amounts from the originally combined voltages, which are also present in the output, unless they have been balanced out. For example, assuming that the two generators 33 and 35 produce tone voltages having fundamental frequency components corresponding to notes C_4 (261.626 c.p.s.) and G_4 (391.995 c.p.s.), having third harmonic components of 784.878 c.p.s. and 1175.985 c.p.s., respectively, the third harmonic difference frequency is 391.107 c.p.s. It will be noted that this differs from the G_4 fundamental by (391.995 - 391.107 c.p.s.) or .888 c.p.s., a sub-audio frequency.

As will be described subsequently in connection with FIGURE 7, I may employ the basic teachings of FIGURE 2 to produce 32 ft. tones from an instrument having no actual generators of tone voltages at the 32 ft. pitch. However, for producing the most desirable celeste type tones, I prefer, as mentioned previously, either to linearly combine with the modulation product voltage another voltage harmonically related to one of the originally combined voltages, or to carry out in air the combination of a modulation product wave with another wave harmonically related to one of the originally combined voltages. Referring to FIGURE 3 for the basic exemplary circuit of such a combination, elements which correspond to those of FIGURE 2 have similar indicia. Thus, in FIGURE 3, I preferably feed oscillations corresponding to tempered fifths from two generators 33 and 35 through suitable decoupling resistors 37 and 39 and key switches 41 and 43, respectively to a square-law modulator 45, as was the case in FIGURE 2. However, in FIGURE 3, mechanically interlocked to the two switches 41 and 43 is another key switch 47 which permits oscillations from a third generator 49, corresponding in frequency to a note an octave below (exactly one-half frequency) that produced by the one generator 35 to pass through a decoupling resistor 51 to be combined linearly or algebraically at the point 52 with the output of the square-law modulator 45, for modification, as desired by a tone-color filter system 53, a stop-switch 54 and subsequent amplification and translation into sound by an amplifier 55 and an electroacoustic device 57.

As is known in the electronic arts, the output of the modulator 45 of FIGURE 3 will contain components whose frequencies are the sums and differences, respectively, of those components of the input oscillations. A strong component of the output will be the difference-frequency between the respective *fundamentals* of the two generators 33 and 35. Since these two generators 33 and 35 produce oscillations corresponding in frequency to a tempered fifth respectively C_4 (261.626 c.p.s.) and G_4 (391.995 c.p.s.) for example—their dif-

ference-frequency voltage will comprise physically in the circuit a voltage whose fundamental frequency component (130.369 c.p.s.) is near, but not equal to, the frequency of the third generator 49, which, by the way of example, may be C_3 (130.813 c.p.s.) an exact octave below the C_4 of the generator 33. Thus, when the output of the third generator 49 is combined algebraically with the output of the modulator 45 there are, physically in the circuit at 52, two distinct component voltages, which, when converted into sound by the projector 57, produce the effect of two notes of slightly different pitch—comparable to the result produced when two organ pipes, tuned slightly apart, are sounded simultaneously. It will be obvious to one skilled in the art that the harmonics also of the oscillations combined at 52 will be slightly different in pitch, respectively, thus further developing the similarity between the acoustic results of my system and that of the celeste tone color of a pipe organ.

When the linear combination is to be carried out in air the circuit of FIGURE 4 will preferably be employed. In this system the operation is the same as in FIGURE 2, except that a second filter 53a stop-switch 54a, amplifier 55a and electroacoustic system 57a are used to convert the voltage from generator 49 to sound.

FIGURE 7 is a chart which shows the relationships between (a) components of two voltages corresponding in frequency to C_4 and G_4 , which are used to obtain the modulation products and (b) the components of the voltage corresponding to C_3 , which voltage is linearly combined with the modulation products to obtain the celeste effect. Column I shows the frequency components in c.p.s. (cycles per second) of note C_4 which, for the purposes of illustration here, is assumed to have four partials which are harmonically related, i.e. integral multiples of the lowest or fundamental frequency component. Column II lists the components of the note G_4 , also having four natural harmonics. Columns III and IIIb list the partials of the new modulation-produced voltage C_3' having component frequencies which are respectively equal to the differences and sums of the fundamental frequencies and the respective harmonics of G_4 and C_4 . Column IV shows the fundamental and twenty-four natural harmonics of a complex voltage corresponding to a tone C_3 , exactly one octave below (i.e., one-half the frequency of) C_4 of Column I. Columns Va and Vb, respectively, show the arithmetic differences in c.p.s. between the respective fundamental frequencies and respective harmonics of C_3 and C_3' . It will be obvious to one skilled in the art that these arithmetic differences will be the "beat rate" between the respective components. Columns VIa and VIb show these respective differences or beat rates as percentages of the corresponding C_3 components in Column IV.

An analysis of the chart of FIGURE 7 reveals several significant points regarding my invention. First, the percentage of .339 (see Column VIa) not only is of the order of .4%, which, as pointed out by Hammond et al. in the aforementioned Patent No. 2,498,367, is productive of a musically desirable chorus effect, but also is a constant percentage throughout the range of both harmonic and fundamental frequencies. This constancy is also desirable, as further indicated by Hammond et al. in the same Patent No. 2,498,367.

It, therefore, follows (see the chart designated as FIGURE 9) that the beat rate doubles from one octave to a higher octave and the beat rate also gradually increases from note to note within any one octave with increasing fundamental pitch. This is in accord with the accepted tuning of celeste ranks in a pipe organ as pointed out by Ernest M. Skinner in The Diapason of July 1, 1952 (page 28).

A further analysis of the chart of FIGURE 7 shows the following several reasons for using "single-sideband"

modulation, selecting only the *lower* sideband (Column IIIa) for the celeste voltage:

(1) The celeste effect due to the upper-sideband (Column IIIb) is small because:

(a) The percent difference is low (.068%) as shown in Column IVb.

(b) The higher frequency harmonic components of the upper-sideband are large in magnitude compared with the magnitudes of the natural higher frequency harmonic components as shown in Column IV. It is well known that maximum cancellation is achieved—to give a beat wave envelope that cyclically varies from two times the maximum of the individual peaks to zero—only when the peak values are equal. In pipe organ work, this means voicing the unison pipe from its out-of-tune celeste pipe to *equal* intensity as well as the same timbre. Actually, a slight departure from this rule is made, to achieve a less obvious beat pattern and, therefore, a more artistic one, the two times peak to zero variation being too extreme. Accordingly, the celeste rank of pipes is usually a little less loud and a little less harmonically developed than the unison rank.

(2) The characteristic (pointed out in 1b above) of the large comparative magnitude of the higher harmonics of the *upper*-sideband would also give the wave form of the resultant tone an unusual amount of higher order harmonics instead of the usual smooth tapering-off harmonic amplitude characteristic of a good musical tone.

(3) Intermodulation resulting in undesirable cross-products (due to a modulation characteristic of higher order than *two*) would be further reduced by the use of single-sideband modulation.

In lieu of single-sideband modulation, in a manner which will be described in detail in connection with FIGURES 5a and 5b, I *may* employ low-pass filters to reduce the prominence of the higher order harmonics present in the upper-sideband (summation) products of the modulation process.

Exemplary instruments

A single-line diagram of the basic circuits of a complete musical instrument employing some of the teachings of my invention is shown in FIGURES 5a and 5b. The instrument is of the "analytic" type, such as that shown by Kock in U.S. Patent No. 2,233,948, wherein complex oscillations corresponding to the notes of a musical scale are selected through key switches, varied as to harmonic content in appropriate filter circuits and converted to desired tones by an amplification and sound projection system. In the Kock-type instrument *octavely-related* oscillations are key-switched respectively to "headers," which collect the oscillations for transmission to respective tone-color circuits, so that harmonically related voices may be produced simultaneously.

In a similar manner, I employ a series of oscillation sources, selected ones of which are shown in FIGURE 5a and designated by C₄, C₄# etc., the remaining sources of the chromatic, equally-tempered scale being omitted to simplify the diagram. Since it is necessary to have 18 generators tuned to the consecutive half tones above the highest note upon which a chorus effect is to be produced, it is convenient to designate this group of generators as a first group, and they have been illustrated fragmentarily at 60a in FIGURES 5a and 5b. In order to make use of the chorus effect achieved by the notes of group 60a, there must be at least 12 additional generators tuned to the consecutive half tones below the lowest note of the first group, and these have been fragmentarily shown at 60b in FIGURE 5a. Also, in the Kock manner, I direct oscillations from these sources through respective decoupling resistors 58 and 59 and through key switches 61, all switches for each key of the keyboard preferably being ganged for simultaneous actuation, to be collected by the 2 ft., 4 ft. and 8 ft. headers designated as 2', 4' and 8', respectively. However, the right-hand two switches in

each gang shown in FIGURES 5a and 5b as 61, according to my invention, select oscillations from sources an octave and an octave plus a tempered fifth, respectively, *above* the source supplying the tone signal to the 8' header. These oscillations are respectively fed to pairs of collectors such as 63 and 65. In the example shown in FIGURES 5a and 5b, the collectors 63 and 65 collect *all* C and G oscillations of the instrument, when they are the lower and upper oscillations, respectively, of any pair selected at the keyboard through the switches 61. Similarly, collectors 67 and 69 collect *all* C# and G# oscillations which are the lower and upper, respectively, of a pair selected at the keyboard. In a similar manner, oscillations corresponding to the remaining octaves of ten half-tones of the scale are keyed and collected from the remaining sources (not shown) in the instrument.

Celeste tone color

In accordance with the principles set forth in FIGURE 2 and the description of it, I may direct the oscillations collected by collectors such as 63 and 65 through low-pass electric filters 71 and 73, if desired for reasons pointed out above with reference to FIGURE 4, of any suitable type known in the art, to a square-law modulator 75. Similarly, oscillations collected by collectors 67 and 69 may be fed through low-pass filters 77 and 79 to a similar modulator 81. Similarly the remaining collectors needed to complete an instrument, feed oscillations through filters and to modulators, respectively. The low-pass filters 71, 73, 77 and 79 etc. will have characteristics such as to limit higher harmonics of an upper-sideband product to levels necessary for bringing any undesired harmonic effect (explained above) to a negligible point. The modulators 75, 81, etc. may be of any suitable type known in the art and may be of the balanced type, arranged so as to produce outputs containing only the lower frequency input oscillations and sum and difference frequencies of the input oscillations. If, however, for the reasons mentioned above in connection with FIGURE 7, I use single-sideband modulators of any suitable type, examples of which are shown in U.S. Patent No. 2,248,250, no low-pass filters are necessary.

The outputs of the respective modulators 75, 81, etc. (FIGURE 5b) are collected by a bus 83 and fed through a decoupling resistor 84 to a tone-color filter 85, if desired, for modification of harmonic content in the manner described by Kock in the aforementioned Patent No. 2,233,948, through a stop switch 93 to output bus 95. Similar to the manner set forth above in connection with FIGURE 3, oscillations collected by the 8' header are directed through a decoupling resistor 86 and may be linearly combined at 87 as indicated by the dashed line 87a with the output of the modulators 75, 81, etc. to obtain the pairs of two distinct frequencies necessary for the celeste effect. Preferably, however, I pass the output of the 8' header through suitable decoupling resistors 86 and 88 to a separate 8' tone-color filter 89 (without the connection 87a to point 87) and switch 91, ganged with stop switch 93, employed for connecting the output 60 of the filter 85 to output bus 95.

In the usual manner I may direct the output of the bus 95 through an amplifier system 97 and electroacoustic system 99. Volume control means (not shown) may also be employed in the usual manner in conjunction with the amplifier 97, as desired.

In accordance with the teachings made in conjunction with FIGURE 4, I may prefer to employ that variation in the system of FIGURES 5a and 5b which is shown in FIGURE 6, in which the output of the 8' celeste tone-color filter 85 is directed via a separate amplifier 94 to a separate electroacoustic system 96.

Nazard and mixture tone colors

According to another aspect of my invention, I have at 75 my disposal, by means of the circuits described above and

shown in FIGURES 5a and 5b—and without adding any more generators and key switches—the necessary voltages to provide a "nazard" tone color (an octave plus a tempered fifth above the foundation tone which, in this case, is an 8' tone), a three-rank mixture (three different "footages" sounding simultaneously from a given stop) and either of two two-rank mixtures. The nazard tone color can be made available by collecting in a bus 101, through a plurality of decoupling resistors 103, the voltages keyed into a plurality of collectors 65, 69, etc. It will be obvious by inspection of the diagram in FIGURES 5a and 5b that when any given key-switch 61 is closed, the fundamental frequency component of the voltage transmitted to the bus 101 will always be a twelfth (an octave plus a fifth) above that keyed into the 8' header. A nazard tone color filter 102, is preferably used to modify as desired, the harmonic content of the output of the bus 101, a switch 104 being provided as shown for selecting the nazard voice. A decoupling resistor 106 may be used, as shown, in the usual manner.

A three-rank mixture can be obtained by combining through a plurality of decoupling resistors 105, 107, and 109 the voltages present on the 2' header, the 4' header, and the bus 101, *respectively*. The combination may be passed with or without filtering, as desired, through a tone-color circuit 111 and a stop switch 113 to the output but 95. Alternately I may pass the outputs of the bus 101 and the 2' and 4' headers through separate tone-color circuits and ganged stop-switches (not shown) to the output bus 95.

Regular tone colors

In the Kock manner, I may provide standard 2', 4', and 8' tone-colors as shown in FIGURES 5a and 5b, by passage of the outputs of the 2', 4' and 8' headers through decoupling resistors 108, 110 and 112, through respective 2', 4' and 8' tone-color circuits (designated further as 2' T.C., 4' T.C., and 8' T.C., respectively) and stop switches as shown, to the output bus 95.

32 ft. and quint tone colors

In FIGURE 8 is illustrated the basic circuit of a musical instrument of the same type as that of FIGURES 5a and 5b. However, FIGURE 8 illustrates (1) the manner in which I obtain a 32' tone-color for a pedal keyboard, and (2) how I can obtain a 10 $\frac{2}{3}$ ' tone-color, sometimes called a "Quint."

In producing one or more 32' voices for a *pedal* keyboard system, along with the usual 16' tone-colors, without the necessity for actual generators producing 32' oscillations, I employ (FIGURE 8) a single series of generators, which, it will be understood may, if desired, be the same ones as those of FIGURES 5a and 5b, if a complete instrument with manual and pedal keyboards is sought. The generators or sources are designated as C₂, C_{2#}, etc., similar to the case of FIGURES 5a and 5b, and will, in the usual complete instrument, comprise a chromatic equally-tempered scale of 5 or 6 octaves. Through suitable decoupling resistors 115 and key switches 117, are passed oscillations from these sources, so as to provide 16' oscillations to a 16' header, 16' oscillations to a collector, such as that designated as 119, and 10%' oscillations (corresponding to a note a tempered fifth above the 16' oscillation) to a collector such as 121. Similarly, oscillations from other sources are supplied (as shown in FIG. 8) to the remaining collectors 123, 125, etc. In a manner similar to the example of FIGURES 5a and 5b, the twelve collectors 119, 123, etc. of FIGURE 8 feed into twelve square-law modulators, only one (designated as 127) of which is shown in the interests of simplification of the diagram. Connections from the twelve collectors 121, 125, etc., are made to the respective modulators 127, etc., as at 129. Thus, the outputs of the modulators such as 127 will contain oscillations

which have, as in the case of FIGURES 5a and 5b, a difference-frequency component which is nearly an octave below that of the 16' oscillations present in the 16' header. The bus 131 collects the respective output from the twelve modulators for modification as desired by a tone-color filter such as 32' T.C. In the usual manner a switch 133 may connect the filter output to the output bus 135 for amplification, volume control and conversion to sound in the amplifier 137 and loudspeaker system 139.

10. Similar to the example of FIGURES 5a and 5b, a 10% or quint tone-color is available in the circuit of FIGURE 8 by directing the output of the respective collectors 121, 125, etc., collected by the bus 141, to an appropriate filter 143 for modification of harmonic content if and as desired. A stop-switch 145 connects the quint to the output but 135 for conversion to sound. In the usual manner, 16' tone-colors can be obtained by connecting one or more 16' filters such as 147, for example, to the 16'

more 16 filters, such as 147, for example, to the 16 header, for transmission as shown in FIGURE 8 to the output system 139 via stop switch 149.

It will be understood that I am not limited to any specific musical intervals as to the oscillations combined. Though the tempered fifth is the exemplary interval, it

- will be obvious that other intervals, such as the tempered fourth, referred to above, may be employed. In the case of the fourth, if, for example, C_4 (261.626 c.p.s.) and F_4 (349.228 c.p.s.) are combined in the manner of my invention, the derived tone will be at 87.602 c.p.s. which is .295 c.p.s. different from F_2 (87.307 c.p.s.) which is two octaves below F_4 . To obtain a celeste effect, then, according to my invention, the F_2' (derived voltage) would be combined algebraically with an F_2 voltage. It will be understood that low-pitched notes and mixtures will be also available from the use of fourths and other suitable intervals in accordance with the basic teachings herein.

While for the purpose of illustrating and describing the present invention particular embodiments have been shown in the circuit diagrams of the drawings, it is to be understood that the invention is not limited thereby since such variations in the circuit arrangement employed are contemplated as may be commensurate with the spirit and scope of the invention set forth in the accompanying claims.

I claim as my invention:

1. An electrical musical instrument comprising a set of audio-frequency sources of electric oscillations having frequencies corresponding to the tones of an equally-tempered scale in which the fundamental frequency of each tone is the twelfth root of two times that of the next lower tone, said sources consisting of a first group of 19 generators tuned to the frequencies of consecutive half-tones and a second group of at least 12 generators tuned to the frequencies of the consecutive half-tones immediately below the first group, a keyboard having 55 keys corresponding to said tones, at least three switches mechanically coupled to each key, the first of said switches being coupled to a first source included in the second group of sources corresponding to the normal tone pitch of the key, the second of said switches being coupled 60 to a second source tuned to a frequency an octave above said first source, and the third of said switches being coupled to a third source a tempered fifth above the second source, a plurality of modulators, a plurality of collectors each connecting the second switch of each 65 octavely related key to one of said modulators, a second plurality of collectors each connecting the third switch of each octavely related key to said one of said modulators, an electroacoustical translating means, and means for electrically connecting the first switch of each key 70 and the output of each modulator to the electroacoustic translating means including switch means selectively associating the outputs of said modulators with the electroacoustic translating system.

2. The combination claimed in claim 1 including circuit means having a stop switch operatively associating

13

the first switch of each octavely related key with said electroacoustic translating system.

3. The combination claimed in claim 1 including circuit means having a stop switch operatively associating the first switch of each octavely related key to a second electroacoustic translating system.

4. The combination claimed in claim 2 including another stop switch selectively coupling said second plurality of collectors directly to said electroacoustic translating system to provide a tone-color a twelfth above the normal pitch for each key.

5. The combination claimed in claim 1 including a fourth switch for each key of said keyboard, circuit means operatively associating said fourth switch with one of said sources to select voltage components from said sources each of which is harmonically related in frequency to the normal pitch for the key, and circuit means including a manually operable stop switch selectively coupling to the electroacoustic translating system the algebraic sum of the voltages collected by said second set of collectors and said circuit means associated with the fourth set of switches, thereby to provide a mixture tone-color.

6. The combination claimed in claim 3 including another stop switch selectively coupling said second plurality of collectors directly to an electroacoustic translating system to provide a tone-color a twelfth above the normal pitch for each key.

7. The combination claimed in claim 1 including a fourth switch for each key of said keyboard, circuit means operatively associating said fourth switch with one of said sources to select voltage components from said sources each of which is harmonically related in frequency to the normal pitch for the key, and circuit means including a manually operable stop switch selectively coupling to another electroacoustic translating system the algebraic sum of the voltages collected by said second set of collectors, and said circuit means associated with the fourth set of switches, thereby to provide a mixture tone-color.

8. In an electronic musical instrument comprising two sources of audio frequency substantially a tempered interval apart, modulating means operatively associated with said sources to produce a frequency slightly below that of a harmonically related tone below the lower of said sources, a third audio frequency source having a frequency harmonically related to the lower of said two sources and slightly higher than the produced frequency, and means operatively associated with the modulating means and the third source for simultaneously converting the produced frequency and the frequency of the third source to sound.

9. A musical instrument comprising the elements of claim 8 wherein the means for simultaneously converting the produced frequency and the frequency of the third generator to sound comprises an electroacoustical device having an input circuit electrically connected to the modulating means and to the third source.

10. A musical instrument comprising the elements of claim 8 wherein the means for simultaneously converting the produced frequency and frequency of the third source to sound comprises a first electroacoustical device having an input circuit connected to the modulating means, and a second electroacoustical device having an input circuit connected to the third source.

11. An electronic musical instrument comprising the elements of claim 8 wherein the modulating means comprises a square law modulator.

12. An electric musical instrument comprising a first group of nineteen generators of periodically varying voltages tuned to the frequency of the consecutive half tones of the equally tempered scale, a second group of at least twelve generators of periodically varying voltages tuned to the frequency of the consecutive half tones immediately lower in frequency than the first group of generators, a square law modulator having a first input cir-

14

cuit connected to each of the generators in the first group and each of the generators of the second group higher in frequency than the twelve lowest frequency generators, each of said modulators having a second input circuit electrically connected to the generator tuned seven half tones lower in frequency, and means electrically connecting the output of the modulator to the generator of the second group having a frequency twelve half tones below the frequency of said latter generator.

10 13. An electronic musical instrument comprising a first group of nineteen generators of periodically varying voltages tuned to the frequency of the consecutive half tones of the equally tempered scale, a second group of at least twelve generators of periodically varying voltages tuned to the frequency of the consecutive half tones immediately lower in frequency than the first group of generators, each generator of the first group and each generator of the second group higher in frequency than the twelfth lowest frequency generator of said group being connected to electrical mixing means, each electrical mixing means being electrically connected to the generator having a frequency a fifth higher than the generator connected thereto, said mixing means producing a frequency slightly below that of the source an octave below the frequency of the lower of said generators, and means for converting the produced frequency and the frequency of the generator an octave below the lower frequency source connected to the mixing means to sound.

15 14. A musical instrument comprising the elements of claim 13 wherein the means for converting the frequency produced to sound comprises an electroacoustical device electrically connected to the mixing means and to the generator having a frequency an octave below the lower of the generators connected to the mixing means.

19 15. A musical instrument comprising the elements of claim 13 wherein the means for converting the frequency produced to sound comprises an electroacoustical device electrically connected to the mixing means, and a second electroacoustical device electrically connected to the generator having a frequency an octave below the lower of the generators connected to the mixing means.

20 16. In an electronic musical instrument comprising two sources of audio frequency substantially a tempered interval apart, modulating means operatively associated with said sources to produce a frequency of slightly different frequency than the tone harmonically related to one of the sources, a third audio frequency source having a frequency corresponding to said tone of the equally tempered scale harmonically related to one of the two sources and slightly different in frequency than the produced frequency, and electroacoustical means associated with said modulating means and the third audio frequency source to convert the produced frequency and third source to sound simultaneously.

25 17. An electrical musical instrument comprising a set of sources of electric oscillations having frequencies corresponding to the tones of the equally tempered scale in which the fundamental frequency of each tone is the twelfth root of two times that of the next lower tone, said sources consisting of a first group of nineteen generators tuned to the frequencies of consecutive half-tones and a second group of at least twelve generators tuned to the frequencies of the consecutive half-tones immediately below the first group, a keyboard having keys corresponding

30 to each half-tone, at least three switches mechanically coupled to each key, the first of said switches being coupled to a first source included in the second group of sources corresponding to the normal tone pitch of the key, the second of said switches being coupled to a second source tuned to a frequency an octave above said first source, and the third of said switches being coupled to a third source a tempered fifth above the second source, a modulator associated with each key having inputs electrically connected to the second and third switches of said key, and an electroacoustic translating means electrically

connected to the first switch of each key and the output of each modulator.
